DANIEL WOODBURY, OF MINNEAPOLIS, MINNESOTA.

Letters Patent No. 70,669, dated November 5, 1867.

MACHINE FOR HAKING BRICK.

The Schedule referred to in these Letters Patent and making part of the same.

TO ALL WHOM IT MAY CONCERN:

Be it known that I, DANIEL WOODBURY, of Minneapolis, in the county of Hennepin, and State of Minnesota, have invented a new and improved Device for Haking Brick; and I do hereby declare that the following is a full, clear, and exact description thereof, which will enable those skilled in the art to make and use the same, reference being had to the accompanying drawings, forming part of this specification.

This invention consists in the construction of a machine by which a number of bricks may be taken from the yard, (where they have been deposited from the moulds to dry,) and carried to and arranged in the pile called a "hake." (The operation of thus handling brick is called by brick-makers "haking.")

By the use of this machine the "haking" is accomplished without handling the brick one by one, as is usually done, as will be hereinafter described.

In the accompanying plate of drawings my improved device for haking brick is illustrated.

Figure 1 represents a side elevation of the machine, showing the arrangement of parts, or the manner of its construction.

Figure 2 is an edge view of the same.

Similar letters of reference indicate corresponding parts.

The machine operates upon the plan of a tongs or grappling-iron, composed of a series of interior grappling-arms or clamps, which are controlled in their movement by the main or outside pair.

A A represents the main pair of clamps, which are jointed together at *a*. B B and C C are interior clamping-arms, which are attached to A A by pivoted connections, as seen at *c c*. They are also pivoted together at *d d*, and where the two shorter arms are connected there is a central arm, D, which hangs loosely upon its pivot. E is a guide-plate, which is connected to A A by supporting-rods *e e*. The ends of the rods *e e* are turned at right angles, and pass loosely through the guide and the clamps A A, so that the guide-plate adjusts itself to the movements of the machine.

The operation or movement of the machine is controlled by the slide or handle F. This handle forms the arc of a circle, and is made of two plates, connected together by stud-pins, leaving a space between them, in which space are arranged rolls marked *f*, two rolls for each arm of the clamps A A, and between which the arms pass freely. These arms, above the connection *a*, are of such a shape that when the sliding handle is raised, the lower ends of the clamps are moved towards the central clamp D, thus grasping the brick. When the handle is lowered, the opposite takes place, the clamp being spread. G is an ear on one of the clamps A, by which the machine is lifted from the brick after depositing them on the hake.

In using the machine, the clamps are placed between the bricks, as they are arranged on the ground, (edge-wise,) when the handle F is drawn up, which clamps or grapples the brick with sufficient force to allow of their being carried to and deposited on the hake. By pushing down the sliding handle, the hold upon the brick is loosened, when the brick are brought into line by pushing against the guide-plate E, when the machine is raised, by taking hold of the ear G, and lifting it from the brick.

A side view of the lower end of each of the clamps is seen in fig. 2, marked H.

What I claim as new, and desire to secure by Letters Patent, is—

A machine for haking brick, constructed and operating substantially as herein shown and described.
